UNITED STATES PATENT OFFICE.

CARL OSCAR NORDENSSON, OF PITTSBURGH, PENNSYLVANIA, ASSIGNOR TO DUQUESNE BURNER SERVICE COMPANY, OF PITTSBURGH, PENNSYLVANIA, A CORPORATION OF DELAWARE.

GAS-BURNER.

1,322,131.

Specification of Letters Patent.

Patented Nov. 18, 1919.

Application filed November 26, 1918. Serial No. 264,191.

To all whom it may concern:

Be it known that CARL OSCAR NORDENSSON, a citizen of the United States, and resident of Pittsburgh, in the county of Allegheny and State of Pennsylvania, has invented a new and useful Improvement in Gas-Burners; and he does hereby declare the following to be a full, clear, and exact description thereof.

10 My invention relates to gas-burners.

The object of my invention is to provide a gas-burner in which the air and gas are so mixed as to produce efficient combustion, thereby obtaining the greatest amount of 15 heat for the minimum amount of gas burned.

To these ends my invention comprises the novel features hereinafter set forth and claimed.

20 In the accompanying drawing, Figure 1 is a longitudinal elevation of a portion of a boiler furnace showing my improved burner applied thereto; Fig. 2 is an enlarged longitudinal section of my improved burner; Fig. 25 3 is a front view; Fig. 4 is a rear view; and Fig. 5 shows a modified form of my invention.

In the drawing, the numeral 2 designates 30 a suitable boiler furnace with the boiler 3 erected thereon, said furnace having the fire-chamber 4.

In the front wall of the furnace is the opening 5 to receive my improved burner, which consists of the metal box or casing 6 35 with the cast-iron or refractory mixing-plate or end-piece 7 having the openings 8 through which the air and gas are discharged and where the combustion takes place.

40 At the outer front end of the casing is the gas-box 9 which is connected up to the gas supply-pipe 10. A suitable valve 11 is provided for controlling the supply of gas to the gas-box 9, and said valve is provided 45 with the lever 12. The rod 13 is connected

up to the lever 12 and to the slide-valve 14 surrounding the casing 6 and controlling the supply of air to the air-chamber 15 in said casing. By this construction the 50 amount of air entering the chamber 15 is proportioned to the amount of gas entering the gas-box 9, so that a proper amount of air to insure efficient combustion is always provided, as the gas-valve cannot be moved

without at the same time operating the air-valve 14.

Connected up to the gas-box 9 are a series of pipes 16 which enter the air-chamber 15 and extend up within a short distance of the openings 8 in the mixing-plate 7, one pipe 60 registering with each opening. From the above it will be seen that the gas and air are absolutely under the operator's control, and further that although the gas and air are kept separate up to within a few inches of 65 the combustion chamber, a mixture with a very fine sub-division is made.

When one or more units are not in use they are closed air-tight, so that no false air can enter the boiler and reduce the efficiency 70 of the other units in use.

Another advantage of this type of burner is that it burns the gas completely with 75 very little excess of air so that the chimney draft can be kept very low.

In Fig. 5, I have illustrated a modified form of my invention in which the burner is L-shaped, the tile 18 being horizontally arranged so that the air and gas are delivered vertically into the boiler, causing the 80 flame to shoot upward and play directly on the crown-sheet and side-plates of the firing-box, this type of burner being more particularly applicable for use in connection with a boiler of the fire-box type for drilling gas 85 or oil wells.

In this form of my burner there is the casing 19, provided with the slide-valve 20, connected up as before to a valve in the gas-pipe 21 in the same manner as previously 90 described, so that the gas-valve and the slide-valve 20 will be operated simultaneously to give a positive and correct regulation of the gas and air. The pipes 22 extend from the gas-box 23 within the air-chamber 24, and said pipes have the upwardly extending connections 25 which register with the openings in the horizontal tile 18.

In this form of my invention the mixture 100 of gas and air receives a violently revolving motion in the fire-box due to the direction of the incoming mixture with relation to the boiler tubes so that the combustion is absolutely completed before the gas enters the 105 fire-tubes.

What I claim is:—

1. In a gas burner, the combination of a

suitable shell or casing, a mixing plate at the discharge end of said casing having openings therein, a box at the front end of said casing, pipes leading from said box into said casing adjacent to said openings in said mixing-plate and registering therewith, said casing having an air-inlet adjacent said box, a slide-valve encircling said shell and controlling said air inlet, and a valve controlling the supply of gaseous fuel to said box.

2. In a gas burner, the combination of a suitable shell or casing, a mixing-plate at the discharge end of said casing having openings therein, a box at the front end of said casing, pipes leading from said box into

said casing adjacent to said openings in said mixing-plate and registering therewith, said casing having an air inlet adjacent said box, a slide-valve encircling said shell and controlling said air inlet, a valve controlling the supply of gaseous fuel to said box, and connections between said valve and said slide-valve whereby said valves are operated simultaneously. 20

In testimony whereof I, the said CARL OSCAR NORDENSSON, have hereunto set my hand.

CARL OSCAR NORDENSSON.
